UNITED STATES PATENT OFFICE

JAMES W. ARTHUR, OF AKRON, OHIO, ASSIGNOR TO THE WILLIAMS FOUNDRY & MACHINE COMPANY, OF AKRON, OHIO, A CORPORATION OF OHIO.

VULCANIZING APPARATUS.

1,308,834.

Specification of Letters Patent. Patented July 8, 1919.

Application filed January 7, 1919. Serial No. 270,028.

To all whom it may concern:

Be it known that I, JAMES W. ARTHUR, a citizen of the United States, residing at Akron, Ohio, have invented certain new and useful Improvements in Vulcanizing Apparatus, of which the following is a specification.

My present invention relates to improvements in vulcanizers designed more especially for the repair of inner tubes of pneumatic tires.

One object of the invention is to provide a self contained unit which can be easily moved about while in operation to any desired place in the work room or garage.

Another object is to provide a construction capable of operating upon a plurality of tubes, all of which will be so disposed as to be free from contact with the flame or any heated part, other than the part being vulcanized.

A further object is to provide a convenient means for storing the fuel supply, and to generally simplify the construction.

With these and other objects in view the invention includes the novel features of construction and arrangement and combination of parts hereinafter described and particularly defined by the appended claims.

An embodiment of my invention is illustrated in the accompanying drawing, in which,—

Figure 1 is a side elevation of my improved vulcanizing apparatus.

Fig. 2 is a front view thereof, and,

Figs. 3 and 4 are detail views.

Fig. 5 is a view of a modification.

Referring by reference characters to this drawing the numeral 1 designates an elongated vulcanizing plate which has a downwardly facing vulcanizing face of suitable width and of a length capable of accommodating simultaneously a plurality of tubes, the apparatus shown in the drawings being designed to handle four, as a convenient number. The back or upper part of the vulcanizing plate is formed as a steam chamber 1^a to which steam is supplied in the manner hereinafter described to secure the necessary vulcanizing heat.

The plate is supported by a standard 2 which is supported at its lower end by legs 2^a and 2^b provided with casters or similar means enabling the vulcanizer to be readily moved from place to place.

The standard is made hollow and closed at its lower end and is adapted to serve as a reservoir for liquid fuel, being provided at its upper end with a filling opening 2^c preferably of funnel shape, and having a shut off cock c.

A boiler 3 for generating steam and carrying a gage glass 3^a is secured to the standard by suitable means, such for example as the clamp 4 and beneath the bottom of the boiler is a liquid fuel burner 5 of the ordinary or any desired type which is connected by a pipe 6 with the interior of the fuel reservoir at the bottom thereof. The top of the boiler is connected by a pipe 7 with the steam space 1^a above referred to.

The fuel is forced to the burner by air pressure which is supplied by a hand pump 8 connected with the standard or pedestal above the surface of the liquid fuel contained therein.

The tubes to be repaired are intended to be pressed against the under or vulcanizing face of the plate 1 and to accomplish this in an expeditious and effective manner I provide a plurality of bell crank levers having arms 9 projecting beneath the vulcanizing plate and carrying presser plates 10 designed to support the looped portion of the tube and to press the patch or part to be vulcanized upward against the heated plate. The blocks are provided with downwardly extending spaced lugs 10^a adapted to straddle the arms 9 and thereby hold the blocks removably and adjustably in position, each block being capable of being slid along the corresponding supporting arm 9 to any desired position. The bell crank levers 9 are fulcrumed on bearing brackets 11 carried by or formed integral with the table or plate 1 and the arms 9^a of the bell crank levers are connected by tension springs 12 to a cross bar 13 supported by uprights 14 from the ends of the plate 1.

The springs tend to draw the arms 9^a upwardly and hence hold the arms 9 and block 10 pressed against the under face of the vulcanizing plate with the tube clamped therebetween.

Means may be provided for adjusting the tension of the springs such as the screw rods 15 threaded through the bar 13 and having their lower ends provided with a swivel connection with the springs.

Each arm 9 is connected by a rod 16 with a

treadle lever 17 fulcrumed upon a rod 18 carried by the legs 2^b, and thus by pressing upon any individual treadle lever the corresponding arm 9 may be depressed against the tension of its spring and the block brought into position to permit the removal of a vulcanized tube or the placing of a fresh tube thereon.

Upon release of the treadle lever the tube will be pressed upward against the vulcanizing plate and it will be sure that the portions of the tube not subjected to vulcanizing action hang free from and out of contact with any heated part and clear of the flame of the burner.

Instead of using springs to secure the clamping effect I may use counter weights, as shown in Fig. 5, in which event the overlying frame 13 is dispensed with the bell 20 crank arms are extended substantially horizontally rearward, as indicated at 9^b and carry weights 12^b which tend to throw the arms 9 carrying the presser pads or blocks upwardly in the same manner as do the 25 springs of the form previously described. The weights are made adjustable on the arms 9^b to vary the pressure and may be locked in adjusted position by set screws 12^c.

In this modification I have shown how 30 the air to the fuel tank may be supplied from a pipe line 8^a instead of a pump carried by the apparatus.

Having thus described my invention, what I claim is:—

35 1. A vulcanizing apparatus comprising a vulcanizing plate having a downwardly facing horizontal surface, a pivoted arm extending substantially horizontally beneath the same, means normally pressing 40 said arm toward the plate, means for swinging the arm away from the plate and a pressure pad having a forked part straddling said arm, and held thereto by frictional contact only, said pressure pad being 45 slidably horizontally on said arm.

2. A vulcanizing apparatus comprising a

hollow standard forming a fuel reservoir, a boiler supported by said standard, a fuel burner connected with said reservoir to receive fuel therefrom, and a vulcanizing member supported by said standard having a steam space connected with said boiler.

3. A vulcanizing apparatus comprising a vulcanizing member having a downwardly facing horizontal surface, a bell crank lever pivoted at one side thereof and having substantially horizontal arms lying respectively above and below said member, a pressure pad carried on the underlying arm, a spring exerting tension on the overlying arm, 60 means for adjusting the tension of the spring and a treadle lever connected to the underlying arm.

4. A vulcanizing apparatus comprising a hollow standard forming a fuel reservoir, a 65 boiler supported by said standard, a fuel burner connected with said reservoir, means for forcing compressed air into said standard, and a vulcanizing member supported by said standard having a steam space connected to said boiler.

5. A vulcanizing apparatus comprising a hollow standard forming a fuel reservoir, and feet at the lower end of said standard carrying wheels or casters.

75 6. A vulcanizing apparatus comprising a hollow standard forming a fuel reservoir, supporting legs diverging from the lower end of said standard, a boiler supported by said standard, a burner below the boiler 80 connected with said reservoir, a pump for forcing air into said standard, a horizontal vulcanizing member carried at the upper end of said standard, spring pressed arms coacting with said vulcanizing member, a 85 rod or shaft supported by two of said legs, treadle levers pivoted to said rod, and means connecting said arms with said treadle levers.

In testimony whereof, I affix my signature. 90

JAMES W. ARTHUR.
